UNITED STATES PATENT OFFICE.

RICHARD ANDREWS, OF CHARLES TOWN, WEST VIRGINIA, ASSIGNOR OF THREE-FOURTHS TO ERICK O. ZYNDA, OF CHARLES TOWN, WEST VIRGINIA.

PAPER TENT.

Application filed August 24, 1921. Serial No. 495,125.

To all whom it may concern:

Be it known that I, RICHARD ANDREWS, a citizen of the United States, residing at Charles Town, in the county of Jefferson and 5 State of West Virginia, have invented certain new and useful Improvements in Paper Tents, of which the following is a specification, reference being had to the accompanying drawings.

10 This invention relates to tents and has for its object to provide a tent which is capable of being made from paper treated to withstand the elements.

It is another object of the invention to 15 provide a tent of this character having a plurality of sleeves adapted to receive ropes or cables for maintaining the tent in its proper shape.

It is also an object of the invention to 20 provide a tent of this character wherein the sleeves are adapted to receive ropes so as to do away with tent poles as far as possible.

It is a still further object of the invention to provide a tent of this character wherein 25 the sleeves intended to receive the ropes are formed in the tent and provided with reinforcing means to prevent breaking and also the entrance of the elements.

With these and other objects in view, the 30 invention consists in the improved construction and arrangement of parts to be herein-after more particularly described, fully claimed and illustrated in the accompanying drawings, in which:—

35 Figure 1 is a fragmentary view in perspective illustrating a wall tent constructed in accordance with an embodiment of my invention;

Figure 2 is an enlarged fragmentary view 40 in perspective illustrating in detail the construction of a sleeve;

Figure 3 is a view in top plan illustrating 45 a tepee or wigwam tent constructed in accordance with an embodiment of my invention;

Figure 4 is an enlarged fragmentary view 50 partly in section and partly in elevation illustrating the arrangement of a tent pole in the form of invention disclosed in Figure 3; and

Figure 5 is a view in plan of the hoop disclosed in this second embodiment of my invention.

This tent may be made in various shapes, 55 for instance, a wall tent, wedge tent, hunt-

er's shelter, tepee or miner's tent, etc. In Figure 1, a wall tent is shown. This tent is intended to be made of paper chemically treated to withstand the elements, said tent including the usual 60 side walls 5 and roof sections 6. Extending longitudinally of the tent at the junction of the walls with the roof sections, is a sleeve 7, said sleeve being disposed 65 interiorly of the tent. A plurality of openings 8 are formed in the upper portion of each of the walls of the tent, through which guy ropes 9 extend, one end of each of said ropes being secured to the ground, while the opposite end is secured to a cable or rope 10 70 which extends through the sleeve 7, the ends of said rope being secured to the ground. Disposed at the apex portion of the roof formed by the section 6 is another sleeve 11, 75 through which a rope 12 is passed, said rope forming the ridge or support of the tent. A pole 13 is adapted to support the end portion of the roof, additional poles being used to support the ridge portion of the roof through the medium of the ropes 80 according to the length of the tent.

As the formation of all of the sleeves is exactly the same, the description of one will suffice for all. The sleeve consists in folding the paper tent at the point where it is 85 desired to shape the tent. The tent is folded inwardly as at 14 to provide a loop, the side portion 15 of the loop extending upwardly beyond the bend of the opposite side portion and is then extended back substantially in parallel relation to the portion 15 as at 16, the remaining portion 17 of the tent being extended in the direction desired. A reinforcing strip 18 is engaged with the outer surface of the portion 14 of 90 the loop, while a reinforcing strip 19 is engaged with the outer surface of the portion 16. The folds are then sewed with a double length of stitching 20 so as to secure the reinforcing strips and connect the end 95 portions of the portions 14 and 15 of the loop. In this way a very substantial sleeve is provided, regardless of the fact that the tent is made of paper and in addition to this, admission of the elements is prevented. 100 The sleeve above described may be disposed at any portion of the tent, either to receive the ridge rope of the tent or the supporting rope of the wall of the tent.

In Figure 3, another form of tent is 110

shown, this tent being the combination of the wall and tepee tents. The apex portion of the tent is provided with an opening 21, the edges of said opening being formed into a sleeve 22 in which a wooden or metallic hoop 23 is disposed. The hoop is intended to engage a shoulder 24 formed on the reduced end of a tent pole 25, said reduced end extending through the hoop to support the tent. Substantially radiating from the sleeve 22 are sleeves 26, said sleeves extending either to the lower edge of the tent, or, if desired to provide a wall, to the junction of the wall with the roof of the tent. These sleeves are formed as above described. Ropes 27 are secured at one of their ends to the hoop, passed through the sleeves and beyond the tent where they are fastened by tent pins or like means, to the ground. If a wall is used in connection with the tent, the wall depends from the ends of the roof, it being unnecessary to extend the sleeves 26 along the walls of the tent.

The other forms of tents mentioned are intended to include sleeves through which ropes are passed to hold said tents in accordance with their construction or shape, each tent, of course, being made of paper.

From the forgoing it will be readily seen that this invention provides a novel construction whereby any form of tent may be made of paper, and used regardless of the weather. Furthermore, in addition to using paper, this construction permits the tent to be supported with less poles than now generally required, so that the tent may be rendered compact for use by travelers such as motor-

ists, as it may be stored in a smaller space.

What is claimed is:—

1. A tent of the character described including a roof portion, said roof being substantially crimped longitudinally thereof at spaced intervals, said crimps projecting inwardly of the roof to provide sleeves for the reception of supporting means, reinforcing strips disposed at the base of the crimps, and means for securing said strips to the crimps adjacent the junction of said crimps with the roof.

2. A tent of the character described including a roof portion, said roof being substantially crimped longitudinally thereof at spaced intervals and inwardly of the roof to provide sleeves, a reinforcing strip engaged with one side of the crimp at the base of the crimp interiorly of the roof, a portion of the roof adjacent the opposite side of the crimp being folded back upon said side of the crimp, and a reinforcing strip engaged with the outer face of the last mentioned fold, exteriorly of the roof, said crimps, folds and reinforcing strips being secured by stitching.

3. A tent of the character described including a roof, portions of said roof being folded inwardly of the tent at spaced intervals to provide sleeves, and reinforcing members disposed on each side of the outer faces of the folds, said reinforcing members being secured to the fold to provide a sleeve and watertight seam.

In testimony whereof I hereunto affix my signature.

RICHARD ANDREWS.
